Cutting Cloaks.

No 13926.

Patented Dec. 11. 1855

UNITED STATES PATENT OFFICE.

A. S. THOMPSON, OF ALBION, PENNSYLVANIA.

CUTTING CLOAKS.

Specification of Letters Patent No. 13,926, dated December 11, 1855.

To all whom it may concern:

Be it known that I, AMASA S. THOMPSON, of Albion, Erie county, Pennsylvania, have invented a new and Improved Changeable 5 Cloak, which can be changed at the pleasure of the wearer into a sack-coat, an Oriental cloak, and the circle-cloak; and I do hereby declare that the following is a full and exact description of the same, reference being had 10 to the accompanying drawings and the letters of reference marked thereon.

Figure 3 is a side view of my "magic" changeable cloak showing all the seams and buttons necessary for the changes designed 15 and which can be shown in a drawing. I cut the cloth from C to D and from E to F, likewise constructing the point F, G, H. The seams C, D, and E F when unbuttoned and the sides N M and P, O, of the sleeve 20 piece L buttoned together forms the sleeve of a sack coat as shown O, P, and M N, Fig. 2. In this arrangement the seam C, D, of the back Q is buttoned to the row of buttons F, R, so that the button I of Fig. 3 is the 25 button I of Figs. 1 and 2. I construct the point F, G, H by cutting it out of the sleeve piece L and inserting another piece of cloth in its place. From G to H are one or more buttons to button the point F, G, H to the piece which is inserted in its place in the 30 sleeve piece L. The point I, Fig. 3 when I wish to change my cloak to a sack coat is buttoned to the point K by a button and buttonhole or loop 1, 2 on the lining of the coat, and the point S is buttoned to the point 35 T by a button and buttonhole or loop 3, 4, also on the inside the coat.

What I claim as my invention and desire to secure by Letters Patent is—

Cutting a cloak from a seamless cloth 40 without sleeves but so that by making four cuts of the proper length for the sleeves, the cloak may be worn as a sleeved sack or over-coat, by merely changing the buttonings, substantially in the manner described.
